UNITED STATES PATENT OFFICE.

ANTHONY ISKE, OF LANCASTER, PENNSYLVANIA.

IMPROVEMENT IN MACHINES FOR SLICING DRIED BEEF.

Specification forming part of Letters Patent No. 144,206, dated November 4, 1873; application filed September 8, 1873.

To all whom it may concern:

Be it known that I, ANTHONY ISKE, of the city of Lancaster, in the county of Lancaster and State of Pennsylvania, have made certain Improvements in a Machine for Slicing Dried Beef, of which the following is a specification:

The object of this invention is to obviate the objections to knives set in frames and used horizontally, or knives otherwise made, and used in cutting dried beef. The objections are overcome by securing the knife in an oblique position in a vertically-sliding frame, so that the edge of the knife comes shear-fashion in close contact with the edge of the stationary holder, both horizontally and vertically, and which contact remains the same, whether regulated to cut thick or thin slices, by making the adjustment independently from that of moving the knife. The resistance and downward pressure of the cutting-edge in its sliding motion secures a clean cut, which has proved to render entire satisfaction.

The accompanying drawings show the construction and combination of the parts, in which—

Figure 1 is a perspective view of the machine. Fig. 2 shows the reverse side of the knife-frame; Fig. 3, the regulating-piece, to adjust the thickness of the slices to be cut, detached.

The base B, with its ledge P to hold against the edge of a table, is provided with two vertical posts, A, joined above by a cross-piece, to leave an open frame. Behind this cross-piece there is a grooved guide, A', above, and a similar one below, in which the frame D D of the knife slides, by its tongue d, in a vertical position. There is an additional bed-piece, B, provided with a vertical end, c, the edges of which may be lined with metal, and come in close proximity to the knife or its cutting-edge. The knife E is slightly concave on its side, (the edge is straight,) and firmly attached to the frame D and portion F of the back, which, with the knife, remain in a fixed position in relation to the inner edge of the bed B' C, on which the beef to be sliced is put and held by one hand, while the knife is propelled by the handle H on the sliding

frame, causing a downward pressure against the resistance of the base and back B' C.

Knives fixed in horizontal frames, over which the dried beef is pushed by hand or otherwise, are inclined to press the object outward or choke up; and when the knife itself is set in or out, its action is impaired; hence I form a distinct piece, G, Fig. 3, which has sufficient play to allow of the desired degree of adjustment by means of a plate, L, at one end, or at the apex, and the other end is provided with a shouldered offset. Headed screw-bolts secure this adjusting-piece G at both ends, and the adjustment is made by means of wedges I J, which have a slot to pass in close contact on each side of the bolts, which wedges, with the adjustment made, are held, by the thumb-screws K, in place.

A fair trial of a working machine of full size has given such universal satisfaction as to be deemed of the greatest utility for slicing dried beef.

I am aware that knives set obliquely in frames for slicing cabbage, &c., are not new; but I am not aware that any have been so used vertically to operate shear-fashion, and made adjustable independently of changing the relative proximity of the edge of the knife and edge of the supporting-table for the material. Therefore,

What I claim as my invention, and desire to secure by Letters Patent, is—

1. The oblique knife E, arranged in a vertically-sliding frame, D, and made adjustable by means of a movable piece, G, in combination with the grooved guides A' A', frame A, holding-bed B' C, and base B with its ledge P, the whole substantially as and for the purpose shown and specified.

2. In combination with a knife, E, and frame D, the adjusting-piece G, with its attached plate L, screw-bolts and thumb-screws K, and slotted wedges I J, substantially arranged in the manner and for the purpose shown and set forth.

ANTHONY ISKE.
